US00D984257S

(12) **United States Design Patent** (10) **Patent No.:** **US D984,257 S**
(45) **Date of Patent:** **** Apr. 25, 2023**

- (54) **CANTILEVERED BRACKET FOR A CANTILEVERED STORAGE SYSTEM**
- (71) Applicant: **Elfa International AB**, Västervik (SE)
- (72) Inventors: **Peter Nilsson**, Västervik (SE); **Lars Ryden**, Västervik (SE); **Rolf Henriksson**, Ankarsrum (SE)
- (73) Assignee: **Elfa International AB**, Västervik (SE)
- (**) Term: **15 Years**
- (21) Appl. No.: **29/679,146**
- (22) Filed: **Feb. 1, 2019**

CLAIM

The ornamental design for a cantilevered bracket for a cantilevered storage system, as shown and described.

DESCRIPTION

FIG. 1 is a front perspective view of a cantilevered bracket for a cantilevered storage system;

FIG. 2 is a front elevation view of the cantilevered bracket for a cantilevered storage system of FIG. 1;

FIG. 3 is a rear elevation view of the cantilevered bracket for a cantilevered storage system of FIG. 1;

FIG. 4 is a right side view of the cantilevered bracket for a cantilevered storage system of FIG. 1;

FIG. 5 is a left side view of the cantilevered bracket for a cantilevered storage system of FIG. 1;

FIG. 6 is a top view of the cantilevered bracket for a cantilevered storage system of FIG. 1;

FIG. 7 is a bottom view of the cantilevered bracket for a cantilevered storage system of FIG. 1;

FIG. 8 is a rear perspective view of the cantilevered bracket for a cantilevered storage system of FIG. 1.

FIG. 9 is a front perspective view of a slanted cantilevered bracket for a cantilevered storage system.;

FIG. 10 is a front elevation view of the slanted cantilevered bracket for a cantilevered storage system of FIG. 9;

FIG. 11 is a rear elevation view of the slanted cantilevered bracket for a cantilevered storage system of FIG. 9;

FIG. 12 is a right side view of the slanted cantilevered bracket for a cantilevered storage system of FIG. 9;

FIG. 13 is a left side view of the slanted cantilevered bracket for a cantilevered storage system of FIG. 9;

FIG. 14 is a top view of the slanted cantilevered bracket for a cantilevered storage system of FIG. 9;

FIG. 15 is a bottom view of the slanted cantilevered bracket for a cantilevered storage system of FIG. 9; and,

FIG. 16 is a rear perspective view of the slanted cantilevered bracket for a cantilevered storage system of FIG. 9.

The dash-dot broken lines in the drawings represent the bounds of the claim design and the dash-dash broken lines in the drawings illustrate unclaimed portions of the cantilevered bracket for a cantilevered storage system; all of the broken lines form no part of the claimed design. The cantilevered bracket for a cantilevered storage system is shown with a symbolic break in its length. The appearance of any portion of the article between the break lines forms no part of the claimed design.
